UNITED STATES PATENT OFFICE.

RUDOLPH BUEHLER, OF PHILADELPHIA, PENNSYLVANIA, ASSIGNOR TO PHILADELPHIA HARDWARE & MALLEABLE IRON WORKS, A CORPORATION OF PENNSYLVANIA.

FRAME FOR REGISTERS, HEATERS, VENTILATORS, OR OTHER SUITABLE DEVICES.

1,051,078.

Specification of Letters Patent. Patented Jan. 21, 1913.

Application filed March 5, 1912. Serial No. 681,813.

To all whom it may concern:

Be it known that I, RUDOLPH BUEHLER, a citizen of the United States, residing in the city and county of Philadelphia, State 5 of Pennsylvania, have invented a new and useful Frame for Registers, Heaters, Ventilators, or other Suitable Devices, of which the following is a specification.

My invention relates to a new and useful 10 frame for a register, ventilator or other suitable device, and consists of a frame formed of sections which may be rigidly connected and which may be removed and replaced, and the frame reassembled in a 15 convenient manner while avoiding the loss of the entire box or frame.

The invention is satisfactorily illustrated 20 in the accompanying drawing, but the important instrumentalities thereof may be varied, and so it is to be understood that the invention is not limited to the specific arrangement and organization shown and described.

Figure 1 represents an elevation of a 25 frame embodying my invention. Fig. 2 represents a perspective view of a corner thereof on an enlarged scale. Fig. 3 represents a side elevation thereof. Fig. 4 represents a side elevation showing the parts in separated position. Fig. 5 represents a sectional view on line α — α Fig. 3. Fig. 6 represents an elevation of one of the side plates and the adjacent corners in detached position.

Similar letters of reference indicate 30 corresponding parts in the figures.

Referring to the drawings: A designates a box or frame embodying my invention, suitable for a radiator, ventilator or other device, the same being composed of the top, 35 bottom and side plates, lettered respectively B, C, D. Upon these parts, I provide means for rigidly connecting the same, and, as here shown, the ends of the top plate and of the bottom plate are extended vertically to 40 act with a suitable portion of the side plates and as the same means are employed at the top and bottom, a description of one will suffice.

E designates the sections or plate sections 45 extending vertically forming corners of the box, and projecting from the extensions are the tongues F, which are offset from the outer wall, forming the shoulder G, and

which are suitably cut away to form the shoulder H.

J designates a lug or ear on the side plate D, which forms a recess or groove K between it and the flange L on the said side plate D, which recess is adapted to receive the tongue F, as best seen in Figs. 2 and 3, 55 it being understood that the shoulder G rests upon the upper wall M of the side plates D, and that the shoulder H rests upon the upper wall N of the lug or ear J. The side plate D is provided with openings P, which 60 are adapted to be in register with the openings Q, formed in the tongue F, which are adapted to receive screws or other suitable fastening means, whereby the said tongue F will be securely and firmly connected with 65 the side plate D, thus forming a firm connection for the box, the tongue and sleeves preventing lateral shifting of the side, top and bottom plates one on the other and that the abutment of the various shoulders will 70 sustain the parts, whereby the members forming the box are stiffened and braced, and the sustaining power thereof is accordingly increased, while at the same time as 75 the side plates are imposed on the tongue F, the strength at this point is increased. When 80 the screws or other fastening means are removed, the frame may be dismembered, when if any of the plates are fractured or broken, they may be replaced and the members of the frame secured in the manner 85 above stated, without the loss of the entire frame.

In the corners of the box are the lugs R, 90 with eyes S therein for the reception of the securing rods usual in such cases. It will be evident that the frame or box is adapted for any purpose.

Other modes of applying the principle of my invention may be employed for the mode 95 herein explained. Change may therefore be made as regards the mechanism thus disclosed, provided the principles of construction set forth, respectively in the following claim are employed.

Having thus described my invention, what I claim as new and desire to secure by Letters Patent, is:—

A register-frame comprising side-plates provided with flanges at their inner edges 105 and having lugs upon their inner faces at

the ends of their outer edges forming longitudinal grooves with said flanges, and plates 5 rectangularly bent at their ends to have the edges of such bent ends bear against the ends of said side-plates and formed with tongues projecting from the inner sides of such bent ends to engage and fit within the grooves of the side-plates, said tongues be-

ing offset from the bent ends forming shoulders bearing against the outer ends of the 10 lugs.

RUDOLPH BUEHLER.

Witnesses:

AUGUSTINE C. METZINGER,
WALTER T. FAHY.
